FASHIONED OR SHAPED KNITTED
GARMENT

Leon Silman, New York, N. Y.

Application December 12, 1946, Serial No. 715,704

4 Claims. (Cl. 66—176)

1

The present invention relates to a fashioned or shaped knitted garment for confining the body of the wearer, such as a girdle, a corset, a bathing suit, underwear and the like and to the method of knitting a fashioned or shaped blank from which such garment is made.

By fashioned garments, it is conventionally meant garments that are inherently shaped so that they conform to the body configuration. That is, such garments are suitably narrowed and widened during the knitting operation so that they will conform to the shape of the human torso.

This is distinguished from garments made from materials which are cut to shape, which cut materials are then sewn together to form the garment. It is also distinguished from seamless garments, the material forming which is knit at those portions which form the narrower parts of the garment with a relatively great tension and knit with less tension at those parts which form the wider parts of the garment and so by relative contraction give the garment the desired shape.

Where the shaping is dependent upon differences in tension, it will be apparent that after a period of wear and washing, the different tensions in the courses of yarn of the material from which the garment is formed will tend to equalize since the greater tension will be lost after such period and cleaning. Thus, after this period and washing, such garments have lost their shape.

Those garments which are made from materials that are cut to shape are relatively costly to make and are not truly fashioned or shaped and do not give the service or wear that is attained with garments made according to the present invention.

The garment with which the present invention is concerned, in distinction, is formed from a blank of material that is shaped in the knitting process so that when the blank is sewn together there is formed a garment that is inherently narrow at a selected portion and wider at a different and contiguous portion.

In the practice of my invention, the material from which my shaped or fashioned garment is made, may be knitted on both circular knitting machines as well as straight or flat bed knitting machines and is illustrated in this description as applied to a knitted girdle.

In the practice of my invention, I knit a strip of material containing a plurality of blanks each of which has a shaped panel therein that is formed by knitting in selected courses a stitch that is comparatively short in one direction and combining such a stitch in the same selected course and other courses with a stitch that is relatively longer in the same direction. Each blank thus formed is sewn together so that the

2

shaped panel will be positioned on the body of the wearer with the narrower parts of the thereby formed garment positioned where desired.

A tuck stitch forms in the direction of knitting a shorter stitch since it is formed on a regular stitch, in the combination of which the regular loop is somewhat longer and the tuck loop in effect has no length at all. To put it another way, in the combination, the regular loop also is somewhat narrower and the tuck loop also is somewhat wider.

In the practice of the invention therefore, in the unshaped portions of the blank, I form the courses of regular loops and in the shaped portions of the blank, I include in selected courses, commencing at certain wales, tuck loops. This narrows and widens portions of the knitted fabric or material and forms in it shaped panels separated by unshaped sections around the fabric at right angles to the direction of knitting.

In knitted fabrics, each course of yarn is knitted so that the fabric comprises a series of adjacent wales referred to as needle wales and as sinker wales. A series of vertically running loop heads formed by the needles being called a needle wale and a series of vertically running loop heads formed by the sinkers being called a sinker wale.

In knitting, a fabric formed from the simplest stitch is referred to as a plain fabric formed from plain stitches. The yarn forming the plain stitch of such fabric continues from the head of the needle loop at the sides thereof into the head of the adjacent sinker loop. In the specification, the term "regular loop" signifies only a V-shaped loop with the point upward and the sides that extend down from the head thereof.

The term "regular stitch" signifies the V-shaped loop, the sides extending down therefrom and the adjacent sinker loops with which they communicate.

A "tuck stitch" is in a sense a defect in the plain stitch forming a plain fabric but is a defect that is systematically produced. The "tuck stitch" is the result of failing to cast off the loops on certain pre-selected needles so that the head of a regular loop is not produced. In the following description, the term "tuck stitch" signifies a V-shaped loop with the point upward, together with a regular loop or a held loop from a lower course, through both of which a loop from the next higher course is drawn. The term "tuck loop" refers only to the V-shaped loop of thread with the point upward. The term "held loop" refers to a long loop which has been held over a course.

The sides of the regular loops appear in the same wales as do the heads of these loops, whereas the sides of the tuck loops extend through the sinker wales on each side of the needle wales in which the heads of the tuck loops appear.

Therefore, a tuck loop in a needle wale is shorter than a regular loop in that wale but is of greater extent coursewise than the corresponding regular loop.

If made on a circular knitting machine, the resulting seamless tube is cut at right angles to the courses to open it and the then resulting material or the material knitted in a flat or straight bed machine is cut substantially parallel to the courses to form separated blanks each of which is then turned 90° to thus properly position the shaped panels so that when the open ends of the material are sewn together, the shaped panels will be at the sides of the thereby formed garment.

In the invention here contemplated therefore, the wales of the material forming the garment run around the body of the wearer whereas the courses of yarn or thread run from the upper edge to the lower edge of the garment.

The shaped or fashioned garment contemplated by my invention is comparatively less costly to produce and therefore relatively inexpensive thus making it available to many users who otherwise could not, because of the cost, wear shaped or fashioned garments, which are considered a more desirable and superior garment.

Further, the rate of production of the shaped or fashioned garment here contemplated since it may be made on conventional circular or flat or straight bed knitting machines is considerably greater than that of prior shaped or fashioned garments made on the same machines.

Other objects and advantages of the present invention will be further apparent from the following description and the drawings relating thereto, in which

Fig. 1 is a plan view of a continuous strip or length of seamless knitted material formed according to my invention with a circular knitting machine and constituting a plurality of girdle forming blanks, the strip of material being broken away to condense the drawing

Fig. 2 is a plan view of a girdle forming blank cut from the strip or length of material illustrated in Fig. 1 and which blank is broken away to condense the drawing

Fig. 3 is a side view of a torso on which is worn a girdle made according to my invention

Fig. 4 is a schematic diagram of an example of a stitch arrangement that may be used to make a girdle forming blank knitted according to my invention.

Fig. 5 is a schematic diagram of a portion of a fabric and illustrating the arrangement of stitches in the example shown.

Referring now to the drawings, a length of seamless tubing or sheathing 10 (Fig. 1) from which the girdle forming blank 12 (Fig. 2) here contemplated may be knit on the circular knitting machine 14, which is of a conventional type and need not be described or illustrated in detail.

It will of course be understood that a conventional straight or flat bed knitting machine may be used, in which case a substantially flat open sided length of material, instead of a seamless tube or sheath, is formed and from which a blank 12 may be formed.

It will of course be understood that the knitting machines used in the practice of my invention will be provided with a suitable cylinder, needles of proper size, proper chain control for the cam operating mechanism and a tensioning device suitable to operate on elastic or rubber

yarn, should that be used in knitting the material from which the garment is to be made.

As pointed out, shaped or fashioned garments are formed in the knitting operations so that they will naturally or inherently conform to and assume the configuration of the body. This is accomplished by widening the garment, if a girdle, at the hips of the wearer and narrowing it above the hips and, if desired, at the lower portion of the garment.

In the practice of my invention therefore, I contemplate providing a girdle 16 (Fig. 3) having a shaped section or panel 18 and 20 at each side thereof and which sections are preferably formed by knitting tuck loops in certain selected courses at selected wales, as I will further describe and which tuck loops are shorter in the direction of knitting (arrow 22, Fig. 1).

The shaped sections or panels 18 and 20 are bounded respectively by the unshaped sections 24 and 26 and 28 and 30. These unshaped sections are preferably formed by knitting all the other courses of regular loops, as will be further described and which in the direction of knitting (arrow 22) are relatively longer than the tuck stitches.

According to my invention, I contemplate knitting a continuous or unbroken strip of material 10 (in the illustration a seamless tube or sheath) with a conventional knitting machine (in the illustration a circular knitting machine), which strip of material comprises a plurality of units 30 (Fig. 1) each of which, when the strip or length 10 is suitably cut constitutes a girdle forming blank 12 (Fig. 2).

In order to provide a mark for identifying the leading edge 32 of each unit 30 and therefore one edge 33 of a blank 12, I prefer to knit into the strip or length of material 10, prior to commencing the knitting or formation of each unit, a separating yarn or yarns, preferably of different color, along the line A—A extending across the width of the strip or length 10.

In order to mark the rear edge 34 of each unit 30 and therefore the other edge 35 of the blank 12, I also prefer to provide in the knitting of the strip or length of material 10 upon completing knitting of each unit, a separating yarn or yarns along the line B—B extending across the width of the strip or length of material. Thus, the beginning and ending of each unit 30 is well defined by the separating yarns A—A and B—B.

Upon completion of knitting the length or strip of material 10, which may be indefinite in length and comprise an indefinite number of units 30, it (the length or strip) is cut along the lines A—A and B—B to form a plurality of closed tubes or sheaths, each of which corresponds to a unit 30. Each thus formed tube or sheath is opened along the side 36 to form a blank 12 having shaped panels or sections 18 and 20 to which reference will be made in greater detail hereinbelow.

It will of course be understood that where the strip or length of material 10 is knitted on a straight or flat bed machine, it will be unnecessary to cut it as is done with the sheath along a side 36, since a strip or length open at each side is formed by such a knitting machine. At any event, upon separating the units by cutting such a strip along the lines A—A and B—B, the blank 12 will be formed.

The thus formed blank 12 is turned around 90° into the position illustrated in Fig. 2 with the courses of yarn 38 and 40, by means of which the shaped sections or panels are formed and to

which more detailed reference will be made, substantially parallel to the sides 33 and 35. The cut edges 36 then form the top edge 42 and the bottom edge 44 of the blank 12 (Fig. 2).

In order to form the girdle 16, the sides 33 and 35 are then secured together, preferably at the rear of the garment by any satisfactory means such as sewing so that the shaped panels 18 and 20 are positioned at the sides of the torso. The dimensions of the shaped sections 18 and 20 and the unshaped sections 24, 26 and 28 are chosen so that they will be positioned at the selected parts of the body and will be narrower and wider where desired.

Commencing with the leading edge 32 of a unit 30, an unshaped rear section 24 is formed by knitting courses 46 of such stitches that the loops thereof have a selected length and width, such as the regular loops 48, illustrated in Fig. 4.

The section 24 is then knit completely with regular loops until the dividing or boundary line of the shaped section 18 is reached, which dividing or boundary line is contiguous to course 1, which consists completely of regular loops (Fig. 4).

Thus, the unshaped panel 24 (as well as all other unshaped panels 26 and 28) comprise courses, the loops 48 of which have a basic length.

Upon reaching course 2 it is knitted of regular loops 48 until first wale 58 (from left to right of Fig. 4) is reached, when a tuck loop 52 is made. In the illustration shown, I form tuck loops in alternate wales in each course in which the tuck loops are provided until wale 58 is reached, where three tuck loops are formed. Thereafter, wales 58 containing three tuck loops alternate with wales 50 containing two tuck loops.

It will be apparent now that since a tuck loop has no substantial length in the direction of knitting 22, the wales in which they are formed are shorter in the direction of knitting than wales formed only of regular loops to thus selectively determine the shape of the fabric by selecting the number of tuck loops 52 in any wale.

Thus, the fabric at the wales 54, which comprise only regular loops (that is, loops of a selected basic length) is longer than the contiguous wales 56 (which in the example of six courses as illustrated in Fig. 4 have but one tuck loop), since they (wales 56) include loops of a selected shorter length, the tuck loops. The latter wales 56 are in turn longer than the contiguous wales 58 and 50, which wales 58 contain three shorter or tuck loops and wales 50 two shorter or tuck loops. The example of knitting shown in Fig. 4 is by way of illustration, since it will be recognized that various shapes may be formed by knitting stitches having the basic length at the wider portions of the garment and stitches having the shorter length in any relative position to give the desired shape at the narrower portions of the garment.

To sum up, therefore, more or less than six courses containing the shorter loops, such as the tuck loops 52, may be varied with one or more courses containing only the longer or regular loops 48 and courses having any selected number of shorter and longer loops may be knitted in those wales of the fabric in such relative position or sequence as will give to the garment the desired form and shape. In this connection, it should also be recognized that blanks which are

narrowed and widened through the width of the fabric as it is knitted are turned around ninety degrees so that the narrow and wider parts are positioned at the sides of the body on which the therefrom formed garment is worn.

It will be further recognized that instead of the combination of regular and tuck loops illustrated, a tuck stitch may be knitted in all the courses throughout the garment and where it is to be shaped, a double tuck stitch will be formed in the selected wales at that part of the garment. To continue, upon reaching course 3, tuck loops 52 are preferably knitted in alternate wales 56 and upon reaching course 4, the tuck loops are also knit in alternate wales as is true with courses 5 and 6. The spacing of the tuck loops is such that the shorter stitches will appear in greater number in wales such as 58 and 50, gradually merging into wales having a lesser number of shorter loops, such as wales 56 until wales having only the longer loops such as wales 54 are reached.

Thus (Figs. 1 and 2), the unshaped section 24 is knit with courses 46 which are formed of loops which are the longest, such as regular loops 48 and upon reaching the boundary line of section or panel 18 it is knit with courses 38 in which shorter loops such as formed with tuck stitches are relatively arranged to give the desired shaped panel or section.

In that portion of the shaped sections or panels 18 and 20, the courses between wales at C and D (Fig. 4) are all provided with the shorter stitches in such sequence of knitting that that portion is relatively narrow. From D to the left of Fig. 4, the courses of yarn are provided with the shorter stitches in wales so spaced and combined with longer stitches that the courses fan outward from the center of the sections at D to provide a relatively wider portion at E. If desired, this comparatively wider portion from E (although it need not be illustrated since it can be obtained by the proper combination of longer and shorter, regular loops and tuck loops as described with reference to the portion C to D), may extend into a narrower portion.

In other words, the courses of yarn near the upper edge 42 form the narrowest section since they have the greatest number of tuck loops in the wales which extend into a somewhat wider section since the courses have a comparatively smaller number of tuck loops in the wales, then form the widest section since only regular loops are formed in the courses in all the wales and if desired extend into a somewhat narrower section in which the courses have corresponding tuck loops in the wales. In the illustration shown in Fig. 4, each group of six courses 38 form shaped ribs 39 between which are knitted courses of regular loops to form the ribs 41. Thus, each shaped panel 18 and 20 is formed from a rib-like structure that defines it from the unshaped sections of the garment 16. It will of course be understood that the number of ribs 39 and 41 may be varied in combination to give the shape to a panel that is desired.

Again, upon reaching the unshaped panel 26 (Fig. 2), all courses 60 are knit with the longest loops, that is as with regular loops 48 and upon reaching the shaped panel 20, short loops, such as those formed by the tuck loops 52, are knit into the courses 40 in the desired relative arrangement to form the selected shape for the panel or section 20.

Again, upon reaching the unshaped panel 28,

its courses 62 are formed of the longest loops, such as the regular stitches 48 until the rear edge 34 is reached and the distinguishing yarn or yarns along the line B—B knitted into the length or strip 10.

The above described schedule of knitting operations may be repeated in succession as a continuous consecutive series of operations to provide a continuous, unbroken strip or length of fabric or material comprising a plurality of contiguous units from which a plurality of blanks may be formed and each of which blanks may then be made into a shaped garment, such as a girdle.

By reason of the described construction, it will be apparent that each section may be knit independently of any other section and therefore, if desired, the shaped sections may be knit with a relatively loose stitch to give them a two-way stretch, whereas the unshaped sections, which may be positioned at the front and rear or at such other selected portions, may be knit with any inelastic yarn having a relatively tight stitch to thus provide portions of the garment, for example the girdle, that are comparatively non-stretchable to thereby give to them the sought for and desired supporting qualities and characteristics without the necessity or provision of additional reinforcing or supporting panels, such as found in prior art garments.

It will be further apparent that the unshaped section may be positioned in any desired relation to a shaped section and that the unshaped section may be knit with any suitable knitting stitch which may be different from that of the shaped section, it being necessary only that the length of the stitch in the shaped section be different from the length of the stitch in the unshaped section.

It will of course be further understood that the unshaped sections 24, 26 and 28 may be omitted and the garment shaped by knitting in the unit between the boundaries 32 and 34 commencing with the edge (side) 36, a narrow part, as desired, from C to D (Fig. 4), which merges into a wider part from D onward. Thus, each unit 10 from wales 58 to wales 54 (Fig. 4) will include in the desired relative sequence, stitches of a shorter length in the direction of knitting and in wales 54 stitches of the longer basic length.

Thus, the resulting blank 12 (Fig. 2) from side edge 33 to side edge 35 and the upper edge 42 to D will be narrowest since it will include stitches of the shorter length and from D to the lower edge 44 will be widened out since it will be formed from a lesser number of stitches of the shorter length.

Referring to Fig. 5, in order to further clarify my invention to those skilled in the art, I have schematically illustrated the arrangement of stitches in the example shown in Fig. 4 with a customary knitter's diagram. In this diagram, each dash represents a regular stitch 48 and each cross a tuck stitch 52. Since the tuck stitches are shorter than the regular stitches, the ribs 49 fan outward since they occupy less space than the ribs 41.

It will also be understood that varied numbers of courses containing the shorter loops may be interspersed with varied numbers of courses containing only the longer loops to thus give to the garment any desired shape without the provi-

sions of the separate panels illustrated in the figures.

It will be understood that I do not intend to be limited by the terms used in the description of my invention, such terms being those commonly used in the trade and being interchangeable with each other.

As various possible embodiments and modifications might be made of my invention, it is to be understood that all matter herein set forth or shown in the accompanying drawings is to be interpreted as illustrative and not in a limiting sense.

I claim:

1. A full fashioned girdle widened and narrowed to conform to the body configuration of the wearer of the girdle, having a front panel having needle wales of regular loops whereby said front panel is unshaped, side panels having needle wales of tuck loops and needle wales of regular loops, said needle wales of tuck loops occurring in the side panels in selected sequence with the needle wales of regular loops whereby each side panel uniformly changes from a narrow shaped section into a widened shaped section and from the said widened shaped section to a narrow shaped section and a back panel having needle wales of regular loops.

2. The full fashioned girdle of claim 1, said wales being disposed laterally around the body when the girdle is worn and the courses disposed longitudinally of the body when the girdle is worn.

3. A full fashioned garment widened and narrowed to conform to the body configuration of the wearer having courses of yarn comprising regular loops and tuck loops in selected sequence and courses of yarn comprising regular loops, said courses of yarn extending vertically upon the garment being worn, said regular loops and said tuck loops forming needle wales in selected sequence to shape the garment to conform to the body configuration, said wales disposed laterally about the body of the wearer upon wearing the garment.

4. A full fashioned garment formed from a continuous strip of knitted material having courses of yarn comprising regular loops and tuck loops in selected sequence and extending longitudinally in the garment when worn, the wales of said garment comprising regular loops and tuck loops in selected sequence and disposed laterally around the garment when worn, the wales forming shaped portions of the garment having narrower and wider sections.
